UNITED STATES PATENT OFFICE.

LUCIUS FREEMAN LITTLE, OF OWENSBORO, KENTUCKY, ASSIGNOR TO ANGLO-AMERICAN MILL CO., OF OWENSBORO, KENTUCKY, A CORPORATION OF KENTUCKY.

FLOUR-MILL.

1,244,219.

Specification of Letters Patent. Patented Oct. 23, 1917.

Application filed December 22, 1916. Serial No. 138,423.

To all whom it may concern:

Be it known that I, LUCIUS FREEMAN LITTLE, a citizen of the United States, residing at Owensboro, in the county of 5 Daviess and State of Kentucky, have invented new and useful Improvements in Flour-Mills, of which the following is a specification.

The present invention relates to flour mills, and particularly that type known as self-contained mills in which the roll section, containing the break and reduction rolls by which grain is reduced, and reel or bolting section, where it is sifted out and 15 purified, are arranged in close proximity to each other, so that "short process" milling is effected, and the instrumentalities having to do with the reduction of grain and bolting of flour are compactly and 20 closely arranged.

In mills of this type it is customary to incase the break and reduction rolls in a substantially tight casing, and the bolting reels are inclosed in an independent casing, 25 the two casings being adjacent each other and connected by conveyers, usually of the screw type, which transfer the stock as it comes from the break and reduction rolls, from the roll section to the reel section, 30 these conveyers being inclosed in close-fitting housings through which the stock is fed by the action of the screw conveyers.

This type of mill, while very efficient, must be thoroughly aerated and cooled, particularly in the reel section side, for the reason that in a self-contained and inclosed structure of this kind the heat generated in the roll section being taken up by the stock, will unduly heat the reel section when 40 the stock is transferred for bolting and purifying, and it sometimes happens that sufficient heat will be generated to cause condensation or "sweating" in the reel section, which is, of course, objectionable.

Various means have been provided for overcoming this difficulty, such as the provision of blowers, or suction fans, to effect a draft through the different parts of the mill, and while this, to some extent, relieves 50 the difficulty, it has not proved entirely satisfactory; and, furthermore, the addition of fan blowers, or the like, adds materially to the cost of the mill.

It is with the object of overcoming this 55 stated objection, and doing away with the

necessity of fan blowers to cool the mill, that I have devised the present construction, and I accomplish this by providing air inlets between the roll section and the reel section, which will admit cool air to the 60 stock in transit from the roll section to the reel section, whereby that stock will be delivered to the reel section thoroughly cooled and aerated, and the objectionable "sweating" in the reel section overcome. 65

In order that the invention may be understood by those skilled in the art, I have shown in the accompanying drawings one embodiment thereof, but it will be understood that this is illustrative, and that variations from this specific embodiment may be made within the range of mechanical skill without departing from the spirit of my invention. 70

In the drawings, 75

Figure 1 is a view partly in section of a mill of the general type referred to, this showing being more or less conventional to illustrate the general class of mills;

Fig. 2 is an enlarged detail view of one 80 of the housings for the conveyer which transfers the stock from the roll-section to the reel-section, showing the air inlet therefor;

Fig. 3 is a plan view of the upper part 85 of the conveyer housing;

Fig. 4 is a transverse section of the housing shown in plan in Fig. 3.

Referring to the drawings by numerals, like numbers indicating like parts in the 90 several views, 10 indicates a roll-section which is provided with any suitable breaking and reducing means, such as the rolls 11 and 12, which are the break rolls, and the rolls 13, which are the reduction rolls, 95 only one set of which is shown, it being customary to provide two sets of reduction rolls, although it will be understood that, so far as the breaking and reducing rolls are concerned, it is immaterial how many 100 are employed, or their particular arrangement, and these breaking and reducing instrumentalities, as shown, are inclosed in a substantially tight casing.

Adjacent the roll-section is the reel- or 105 bolting-section 14, containing the bolting reels which, as is customary, are made up of the fine mesh-section 15 and the coarse mesh-section 16, but it is immaterial, for the purposes of the present invention, what 110

the particular arrangement of screening surfaces may be, and this battery of reels is, as shown, inclosed within a substantially tight casing.

- 5 The two sections of the mill above described, are connected by conveying instrumentalities 17, which, in the form here disclosed, are screw conveyers, these screw conveyers 17 being so disposed with respect to 10 the break and reduction rolls in the roll-section 10, as that they will receive the stock from the rolls and convey it each to the respective bolting reel which is to handle the stock. The screw conveyers 17, as 15 shown, preferably pass through housings 18 which open at their opposite ends into the roll-section and the reel-section, respectively, thus forming a completely inclosed casing through which the stock is fed by 20 the screw conveyer 17.

The action of the screw conveyer 17 in these closed housings is a pumping action, in that they not only force the stock along, but also cup and pump air across from the 25 roll-section to the reel-section, and this transfer of air from the roll-section is also induced by the action of the beaters, not shown, within the reels in the reel-section, so that there is a constant pumping of the 30 air with the stock from the roll-section to the reel-section, and as this air and the stock becomes heated, due to the action of the break and reduction rolls, it is delivered to the reel-section at a higher temperature 35 than is desirable.

In order to insure reduction of temperature, and the delivery of stock and the air coming from the roll-section at a proper temperature in the reel-section, I provide 40 the housing 18 with an air inlet, and I preferably accomplish this by providing a supplemental housing made up of two sections bolted together, and adapted to receive, in properly formed seats in their ends, the 45 housings which project from the roll-section and the reel-section, as shown in Fig. 2. The upper section of this intermediate housing is provided with an air inlet 19 which, in the form shown, is a rectangular 50 opening. This inlet 19 is preferably screened by means of a screen 20 mounted upon a frame 21, which is suitably secured, as by screws 22, in the opening, the frame 21 preferably being arranged as shown in 55 Fig. 4, namely, snugly fitted to the inclined side walls 23 which define the inlet opening, this screen preventing any foreign matter falling into the stock as it passes from the roll section to the reel section.

60 With this construction it will be apparent that the action of the conveyer, and the suction of the fan in the bolting reels, will cause an intake of cool air by way of the inlet 19, so that the stock will be delivered 65 to the bolting section at a temperature

which will do away with sweating, and will also do away with the necessity of blower fans for cooling the mill.

It is desirable to regulate this inlet 19 so as to vary the amount of air taken in, and 70 while this may be accomplished in a variety of ways, I preferably provide the inlet with a sliding gate 24, which is mounted in slideways 25 formed on the housing, so that it may be opened more or less to give such 75 inlet area as may be desired.

By means of this regulated inlet the conditions as to temperature may be nicely controlled, and sufficient air admitted to meet temperature conditions under which the 80 mill may be working.

Such variations from the construction shown and described as are obvious mechanical expedients for the elements adopted by me, are to be regarded as within my invention, and I do not limit myself, therefore, except as limited by the terms of the appended claims.

I claim:

1. In a mill of the class described, the 90 combination of a roll-section, a reel-section, a conveyer delivering from said roll-section to said reel-section, and means for delivering air to the stock in transit from the roll-section to the reel-section.

2. In a mill of the class described, the 95 combination of a roll-section, a reel-section, a conveyer delivering from said roll-section to said reel-section, and means for delivering air to said conveyer between said roll- and reel-sections.

3. In a mill of the class described, the 105 combination of a roll-section, a reel-section, a conveyer delivering from said roll-section to said reel-section, means for delivering air to said conveyer between said roll- and reel-sections, and means for regulating air delivery.

4. In a mill of the class described, the 110 combination of a roll-section, a reel-section, a conveyer delivering from said roll-section to said reel-section, and a housing for said conveyer having an air-inlet.

5. In a mill of the class described, the 115 combination of a roll-section, a reel-section, a conveyer delivering from said roll-section to said reel-section, a housing for said conveyer having an air inlet, and means for regulating admission of air through said inlet.

6. In a mill of the class described, a roll-section for reduction of the grain, a reel-section independent of said roll-section for bolting of the stock, a conveyer to receive the stock from said roll-section and deliver it to said reel-section, and a housing for said conveyer connecting said roll- and reel-sections, said housing having an air inlet in its upper part, and a gate for said inlet to regulate admission of air.

7. In a mill of the class described, the combination of a casing for the breaking instrumentalities, breaking and reducing rollers in said first casing, a casing for the bolting instrumentalities independent of said first casing, bolting instrumentalities in said second casing, a conveyer housing connecting said casings, and a conveyer delivering from said first casing to said second casing, said housing having an air inlet for admitting air to said housing and bolting section.

8. In a mill of the class described, the combination of a breaking section having a casing, breaking and reducing rolls in said casing, a bolting section having a casing independent of said first casing, bolting instrumentalities in said second casing, a housing connecting said casings and having an air inlet opening for admitting air to said

housing and bolting section, and a conveyer in said housing delivering from said first casing to said second casing, said conveyer being of a type capable of pumping air through said air opening into said bolting section.

9. In a mill of the class described, the combination of a breaking section having a closed casing, breaking and reducing rollers in said casing, a bolting section having a closed casing independent of said first casing, bolting instrumentalities in said second casing, a conveyer housing connecting said casings and having an air inlet opening at its top and between said sections, and a screw-conveyer delivering from said first casing to said second casing.

In testimony whereof I have hereunto set my hand.

LUCIUS FREEMAN LITTLE
